UNITED STATES PATENT OFFICE.

HENRY CLINTON HICKS, OF MINNEAPOLIS, MINNESOTA, ASSIGNOR TO THE AMERICAN LIVE STOCK EXPRESS COMPANY, OF NEW YORK, N. Y.

DOOR FOR STOCK OR FREIGHT CARS.

SPECIFICATION forming part of Letters Patent No. 324,255, dated August 11, 1885.

Application filed May 12, 1885. (No model.)

To all whom it may concern:

Be it known that I, HENRY CLINTON HICKS, a citizen of the United States, and a resident of Minneapolis, in the county of Hennepin and 5 State of Minnesota, have invented certain new and useful Improvements in Doors for Stock and Freight Cars, of which the following is a specification.

This invention relates to the doors of stock 10 and freight cars; and it consists in fitting the doors into the openings or doorways so that their outer surfaces do not project beyond the general surface of the car, and means whereby the door may be moved bodily outward and 15 upward before it is moved sidewise to open it, as hereinafter shown and described.

This door may be applied to nearly all forms 20 of stock and freight cars, but is more particularly applicable to the form of stock-car shown in my Patent No. 288,335, dated November 13, 1883.

To illustrate the application of this invention I have shown it in the drawings applied to the frame-work of a car adapted to the system of stall-bars, feed-racks, watering-troughs, &c., as shown in my patent above referred to, 25 in which—

Figure 1 is a cross-sectional view of a stock-car through the doors. Fig. 2 is a side elevation; and Fig. 3 is a plan view of a section of 30 one side of a car, as shown in Fig. 1, and having my improvements attached thereto.

A is the floor, and B the stanchions or open frame-work, the stanchions being arranged in 35 pairs about six inches apart and with about three feet of space from center to center of each pair of stanchions, the stanchions being intended to serve as guides to the ends of the movable stall-bars.

40 C is the roof, and D D the doors of the car.

In this form of car, and in nearly all forms 45 of stock-cars in which provision is made for separating the animals by stalls or compartments, one or more sets of such stall-divisions occur on the door or doors of the car, and the guides, feed-racks, watering-troughs, &c., being necessarily attached to the door, project 50 so far into the car that it is necessary to modify to some extent the construction of the means for opening and closing the doors.

In the ordinary car, with nothing attached to the inner surfaces of the doors, the custom

is to merely slide the doors to one side upon tracks attached to the sides of the car. In this form of car the doors necessarily project outward beyond the general surface of the car, which under some circumstances is an objectionable feature, rendering it necessary to provide some means for the prevention of the entrance of snow and rain at the sides, as the doors thus operated cannot be closed tightly; whereas with the door shutting into a casing, like an ordinary door, as in the form of door shown in the drawings, they can be made to rest against stops which will make them easily 60 water and snow proof.

Another disadvantage of the sliding door often met with in freight-cars is the fact that the jolting of the car in transit frequently displaces pieces of the freight, and causes them to 70 crowd against the doors and render it very difficult to slide them sidewise. With my form of doors, however, which move outward bodily before they are moved sidewise, all such difficulties are avoided, as, if the freight 75 becomes pressed down against the doors, the outward movement at once relieves this pressure.

The extent of the outward movement is immaterial. In ordinary freight-cars it need not 80 necessarily exceed two or three inches, while in the form of car illustrated in the drawings, and in numbers of other cases of stock-cars similarly constructed with feed-racks, watering-troughs, stall-bars, guides, &c., attached to 85 the doors, it is necessary to throw the doors outward far enough to cause these attachments to clear the frame of the car when the doors are moved sidewise. In the drawings, each of the doors D D will be provided with one or 90 more sets of guides, G G, similar to the stanchions B, except that, unlike the stanchions, they have but one function—viz., to serve as guides to the ends of the stall-bars which come opposite the doors—whereas the stanchions B 95 have the double function of serving as a portion of the frame of the car, and also as guides for the stall-bars.

H' H' represent the folding feed-racks; H² 100 H², the watering-troughs between each pair of the stanchions B and guides G G, and H⁴ and H⁵ the pipes through which the water is supplied to the troughs.

The stall-bars are shown in Fig. 1 and let-

tered K' and K², K² representing the stall-bars opposite the doors, and K' the stall-bars in one end of the car. The stall-bars K' are shown in their lowered position, while the stall-bars 5 K² opposite the doors are shown in their elevated position.

K³ K⁴ represent the chains by which the stall-bars K² are operated. The mechanism by which the stall-bars are raised and lowered 10 forms no part of this invention. They may be conveniently operated by the mechanism shown and described in my above-mentioned Letters Patent, or by the mechanism shown and described in my application for Letters 15 Patent filed June 5, 1885. The lower ends of these chains K³ K⁴ will be arranged to be detached from the car and lifted out of the guides G G when the doors are to be opened. In Fig. 1 the chain K³ and its lower pulley, K⁵, 20 are shown detached from the floor of the car and turned off to one side.

In practice it will be necessary, when the door is to be opened, to disconnect the pulley K⁵ from the outside, (it of course being understood that the stall-bars K² will first have to 25 be elevated,) and then after the door is opened the chain and its pulley K⁵ will hang down loosely in front of the center of the doorway.

Before the cattle are driven into the car, or 30 before they are removed therefrom, the hanging chain will be looped up beneath the roof of the car or disposed of in some suitable similar manner. Then after the cattle are all in 35 position in the car, the chains K³ K⁴ will be dropped down between the guides G G, and the pulley K⁵ hooked into a staple, K⁶, between the lower ends of the guides, or in the floor of the car before the stall-bars K² are run down.

40 The frame-work or sides of stock-cars are formed of open slats, so that it will be an easy matter for the operator to reach in between the slats and manipulate the chains K³ K⁴ and pulley K⁵, above described.

45 The mechanism employed to move the doors outward consists of two small rods, a a, hinged by their lower ends to the inner surfaces of the doors near their upper corners. These rods are connected at their upper ends to two 50 sliding bars, a' a', the latter provided with hooked upper ends adapted to enclose horizontal tracks L L, attached to the sides of the car above the doorways. It will be readily understood that if the rods a a be turned upward at right angles to the door the latter will be moved outward and upward, as shown 55 in Fig. 1, on the left-hand side. I have shown a windlass, M', provided with a ratchet-wheel, b', adapted to be held by a pawl, b², 60 the windlass being journaled in any suitable manner on the outside of the door, centrally, about on a line even with or a little below the lower ends of the rods a a.

65 Small chains or cables d lead from this windlass M' in opposite directions, and pass through the door just below the rods a a

and thence around small pulleys a⁵ secured in brackets a⁶ on the inner surfaces of the doors, and thence up to the upper ends of the rods a a, to which they are attached. The 70 chains or cables d d will be attached to the drum or windlass M' on opposite sides, so that as the drum is revolved in one direction both parts of the chain will be wound upon it, and will be unwound therefrom when the 75 drums are revolved in opposite directions. By this means if the drums be revolved in one direction the cables d d will be wound upon them and draw the rods a a upward and move the doors outward and upward, as shown in 80 Fig. 1 at the left-hand side.

The lower edges of the doors are provided with "points" or "studs" e e, which are adapted to fit into sockets e' e', formed for them in the outer edges of the floor of the 85 car. Usually these sockets consist of or will be formed by straps attached to the edges of the floor A of the car and opening down through the floor, so that any snow or water that may flow down into them will not 90 remain in them and become frozen in cold weather.

I claim—

1. In a stock or freight car, doors and horizontal tracks attached to the car above 95 the doorways, in combination with sliding bars which embrace said tracks and slide thereon, and suspension-rods pivoted to said sliding bars at their upper ends, and to the inner sides of the doors at their lower ends, 100 substantially as set forth, whereby the doors may be swung bodily outward and then be moved parallel with the sides of the car.

2. In a stock or freight car, doors, horizontal tracks attached to the car above the 105 doorways, sliding bars which embrace said tracks and slide thereon, and suspension-rods pivoted to said sliding bars at their upper ends and to the inner sides of the doors at their lower ends, in combination with a 110 windlass mounted on the exterior of each door, and cables which pass through the door and are attached at one end to the windlass and at the other end to the upper parts of said suspension-rods, substantially as set forth. 115

3. The combination, with a stock or freight car, of horizontal tracks L L, attached to said car above its doorways, sockets e' e' in the floor of said car opposite its doorways, doors D D, having studs e e fitting into said sockets 120 when said doors are closed, jointed suspension-rods a a' connecting said doors with said track, windlass M', and chains or cables d d, substantially as set forth.

In testimony whereof I have hereunto set my 125 hand in the presence of two subscribing witnesses.

HENRY CLINTON HICKS.
